UNITED STATES PATENT OFFICE.

WILLIAM H. AIKEN, OF WELLSVILLE, NEW YORK, ASSIGNOR OF ONE-HALF
TO HORACE A. HIGGIE, OF SAME PLACE.

TOOL FOR SHAPING AND SIDE-DRESSING SAW-TEETH.

SPECIFICATION forming part of Letters Patent No. 650,788, dated May 29, 1900.

Application filed July 10, 1899. Serial No. 723,350. (No model.)

To all whom it may concern:

Be it known that I, WILLIAM H. AIKEN, a resident of Wellsville, in the county of Allegheny and State of New York, have invented 5 certain new and useful Improvements in Tools for Shaping and Side-Dressing Saw-Teeth; and I do hereby declare the following to be a full, clear, and exact description of the invention, such as will enable others skilled in

10 the art to which it pertains to make and use the same.

The invention relates to tools for shaping and side-dressing the teeth of saws, and has for its object to increase their efficiency and 15 economy.

The invention consists in the construction hereinafter described and pointed out.

In the accompanying drawings, Figure 1 is a perspective of the improved tool. Figs. 2 20 and 3 are opposite views of a central section passing between the tool-jaws. Fig. 4 is a section in the plane of the handles. Fig. 5 is a plan. Figs. 6 and 7 are perspectives of detachable dies. Figs. 8 and 9 are perspectives 25 of a tooth-stop, and Fig. 10 is a perspective of an eccentric pin.

It will be understood that Figs. 1 to 4, inclusive, show the tool inverted as respects its operative situation.

30 Numerals 1 and 2 denote jaws having a connecting-bolt 3. The rear end of jaw 1 is bifurcated to embrace a reduced portion of jaw 2, as best shown in Fig. 5. The bolt 3 has a flattened portion 3', adapted to slide in a suitably-shaped opening 3" in the jaw 2 to 35 permit adjustment to saw-blades of different thickness.

4 and 5 indicate handles for opening and closing the jaws to operate suitable dies, and 40 6 is a guide comprising an arm having a slot 7 in alignment with the space between the jaws. The guide 6 is fastened to the outside of jaw 2 by screws 6'. The jaws are operatively connected by the medium of arms 8, 45 which arms are loosely supported by an eccentric pin 9 passing through the jaw 2, the parts being held in proper relation endwise the pin by spring-pins 10 and set when adjusted by a screw 9'. The opposite ends of 50 the arms are loosely connected to the handle

4 by a pivot or bolt 11, held in place by nuts 12. The inner end of the handle 4 terminates in a bifurcated arm 13, connected to a lug 14 by a pivot 15 and to the arms 8 by pivot 11, as before described, the construction being 55 such that depressing the handle, the tool being in operative situation, as indicated in Fig. 5, closes the jaws, a reverse movement opening them.

16 denotes dies detachably secured in the 60 proximate faces of the jaws by screws 16'. They are provided with portions variously beveled, as at 17, 18, 19, and 20, to adapt them for shaping and dressing dissimilar teeth.

In jaw 2 is a stop 21, having a projection 21' to determine the position of the saw-tooth. It is adjustably fastened in a suitable seat in 65 jaw 2 by means of a screw 22, abutting against a shoulder 23.

The jaw 2 has a sliding connection with jaw 1 at 3 to permit the die-plates 16 to closely hug the saw-plate.

In operation the tool is applied to the toothed edge of a saw, so that the guide 6 70 embraces it. The pin 9 is turned to tighten the jaws on the saw-blade, and said pin is then set by screw 9'. The stop 21 is suitably adjusted by screw 22 to vary the swaging effect of the dies, which determines the gage. 75 The handles are then used to force the dies 16 against the tooth to shape and press it.

The improved tooth shaper and side-dresser dispenses with springs and also avoids the necessity of using a side file. By its use the 80 swaged tooth can be pressed into perfect and uniform shape. The dies straighten the tooth and at the same time compress the swaging to any desired gage, tapering it in both directions from the point, giving a perfect clearance with the face and point the widest. The dies press the surplus steel to the front of the tooth and obviate the necessity of filing. One set of dies can be used to shape four different styles of teeth.

Having thus described my invention, I claim—

1. In a tool for side-dressing saw-teeth, the jaws, dies secured in the jaws, arms for opening and closing the jaws, and an eccentric

pin pivotally connecting the jaws and arms, whereby the jaws may be adjusted to blades of different thicknesses.

2. In a tool for side-dressing saw-teeth, the jaws, dies secured in the jaws, arms for opening and closing the jaws, and an eccentric pin pivotally connecting the jaws and arms, and means for locking the eccentric pin in variable positions.
3. In a tool for shaping and side-dressing saw-teeth, the jaws, dies secured in the jaws, a handle, and the guide fixed to a jaw, the jaw opposite that to which the guide is fixed being adjustable with respect to the jaw first named, the devices for adjustment comprising the arms, the sliding connection of the jaws, and the eccentric pin connecting a jaw and arms.
4. In a tool for side-dressing saw-teeth, piv-

otally-connected jaws, dies fixed in the jaws, a handle pivoted to one of the jaws, arms pivoted to the handle, and an eccentric pin connecting the arms and the other jaw, as and for the purposes stated.

5. In a tool for side-dressing saw-teeth, jaws, dies fixed therein, means for moving said jaws to and from each other, and a tooth-stop fixed in one of the jaws adjacent the die, and a screw coöperating with the stop and the jaw, whereby operation of the screw will adjust the stop.

In testimony whereof I have signed this specification in the presence of two subscribing witnesses.

WILLIAM H. AIKEN.
